UNITED STATES PATENT OFFICE.

JAMES H. BLESSING, OF ALBANY, NEW YORK.

STEAM-TRAP.

SPECIFICATION forming part of Letters Patent No. 268,384, dated December 5, 1882.

Application filed October 19, 1882. (No model.)

To all whom it may concern:

Be it known that I, JAMES H. BLESSING, of the city of Albany and State of New York, have invented a new and useful Improvement 5 in Steam-Traps, of which the following is a full, true, and exact description, reference being had to the accompanying drawings.

This invention is an improvement upon the machine previously patented to me on the 27th 10 day of August, 1878, No. 207,484, and it contains likewise an improved arrangement of the air-return pipe patented to me on the 16th day of November, 1880, No. 234,386.

The special object of my invention is to increase the rapidity and also the certainty of 15 action of the trap. This I do by an independent receptacle so connected with the main trap as to co-operate with it and aid it in its function.

20 My invention will be readily understood from the accompanying drawings, in which similar letters represent similar parts.

Figure 1 is a plan view of my trap; Fig. 2, a vertical view thereof; Fig. 3, a vertical view 25 thereof at right angles to Fig. 2; Fig. 4, a cross-section through Fig. 3, and Fig. 5 a cross-section through Fig. 2.

A represents the case or exterior of the trap; P, the bucket.

30 K represents the water-inlet pipe, into which the air-returning pipe H enters.

L represents the equalizing steam-pipe, and E the siphon passing down to the bottom of the bucket and connected with the discharge-pipe G.

35 The bucket P travels upon the central guide-rod, g, and is itself provided with a tube, h, surrounding said central guide-rod. The upper end of this tube is provided with collars 40 similar in their operation to those described by me in my previous patent above referred to. The bottom of the bucket P is provided with a pocket or cup, f', extending below the general level of the bottom. This pocket is 45 adapted to enter the corresponding recess F in the casing A of the trap. By this means the trap can be thoroughly emptied of any contained water.

Connected with the trap is the receiver 50 B. This receiver is provided with two connections entering the trap, one connecting with

the bottom of the casing A by pipe J, closed by the check-valve f. The upper part of the receiver B connects by pipe D with the lower part or bottom of the bucket. A deflecting-plate, g', is provided opposite the delivery-opening of the pipe D.

Connected with the upper part of the receiver B is the pipe H, which delivers into the inlet-pipe K through the dip or sealing pipe b. 60 A hand air-valve, e, is provided on top of the receiver B.

The siphon-pipe E is provided with a chamber, C, at its upper extremity, and this chamber connects by pipe a with the pipe D, and 65 consequently with the receiver B.

d is a band-hole for entering the trap, and e an automatic air-valve. Another hand air-valve, k, is shown connected with the chamber C.

70 The operation of my trap can now be readily understood.

The trap is supposed to be connected with a closed pressure system, the return from the coils being connected at the pipe K, provided 75 with a suitable check-valve, and the pipe G communicating with the boiler below the water-level through a check-valve, as shown in Fig. 5. The pipe L is connected with the live steam in the boiler. In starting the trap the 80 air-valve e should be opened, when the water will flow in through the pipe K, entering at first the annular chamber exterior to the float or bucket P. This bucket will then be floated upward, closing the equalizing steam-valve in 85 the pipe L, in the well-known way, when the screw-valve in said pipe L may be opened, and the steam-pressure admitted upon the equalizing steam-valve. After the annular space exterior to the float P has been filled, the water 90 will flow over the upper edge of said float and commence to fill it. It will also fill the receiver B and its connecting-pipes. The water will likewise rise in the pipe E, any air which there may be in it escaping through the connecting-pipe a and air-valve k. After sufficient water has entered the bucket to overcome the 95 flotation of the exterior water, the bucket will suddenly sink and a certain amount of additional water in the annular space will enter 100 the bucket. By this operation the equalizing steam-valve is closed and the water contained

in the bucket begins to be emptied through the siphon-pipe G into the boiler. In so doing the level of the water in the annular space exterior to the bucket is gradually lowered, and 5 the upward movement of the bucket reduced; but after the bucket has been so far emptied as to uncover the lower end of the pipe D, the water in the reservoir B will flow immediately into the annular space, and thereby force the 10 bucket upward with certainty and with considerable force. In this way the equalizing steam-valve is again closed, and a vacuum being formed in the well-known way, the bucket and the receiver B are once more filled. After 15 the trap has commenced its proper operation, the air-valve e may be closed. Then if any air should escape in the chamber C, it will pass by the pipe a to chamber B, and thence by the pipe h through the sealing-pipe b into the 20 livery to the trap. Any air entering the trap escapes by the automatic air-valve c, and the sealing-pipe b will prevent the upward movement of any air through the pipe H. The pipe H is of course reduced to a very small opening, as shown at M. By means of the pocket 25 in the bottom of the bucket, the bucket may be thoroughly emptied of water, thereby increasing the working capacity of the trap. The check-valve f prevents the filling of the 30 chamber B, except through the pipe D, and thereby prevents the rattling noise which might otherwise result.

One of the advantages of the auxiliary receptacle B is that the water therein contained 35 is not brought in contact with the hot steam entering through the equalizing steam-valve, it being found in practice that the water in the annular chamber surrounding the bucket, being highly heated by the steam within the 40 bucket during the process of discharge of the trap, will fly into steam after the equalizing steam-valve is closed and condensation commences, thereby delaying the operation of the trap.

45 By the present arrangement a large body of comparatively cool water is suddenly mingled with the annular stratum surrounding the bucket and its temperature thereby consider-

ably reduced. The addition of this cooler water from the receptacle B likewise aids in condensation, and thereby increases the rapidity 50 of the operation of the trap.

What I claim as my invention, and desire to secure by Letters Patent, is—

1. The combination, with a closed steam-trap, of an auxiliary water-receiver connected with said steam-trap by two connections, one entering said trap below the lowest water level in said trap and the other connected with said trap between the highest and lowest level in 60 said trap, thereby allowing the auxiliary vessel to be alternately filled and emptied, substantially as described.

2. The combination, with a bucket-trap, of an auxiliary receiver, said auxiliary receiver 65 being connected with the trap by two connections, one outside and the other inside of the rising and falling bucket, substantially as described.

3. A siphon bucket-trap provided with a 70 connecting-pipe between the siphon and an auxiliary receiver connected with said trap and with a connection from said auxiliary receiver to the water-supply, substantially as described.

4. A steam-trap provided with an auxiliary receiver connected with said trap by two connections entering the trap at different levels, the lower connection being provided with a check-valve opening toward the trap, substantially as described.

5. A steam-trap provided with a rising and falling bucket, a siphon for discharging said bucket, and an auxiliary receiving-vessel located above said trap and adapted to be filled 85 from and to discharge into the said trap, and with the connections shown, whereby said auxiliary vessel discharges into the trap only after the bucket has been substantially emptied, thereby insuring the closing of the equalizing 90 steam-valve, substantially as described.

JAMES H. BLESSING.
